UNITED STATES PATENT OFFICE.

ADELARD E. RAVENELLE, OF NORWICH, CONNECTICUT.

LAY-MARK PREVENTER.

1,409,778.

Specification of Letters Patent. Patented Mar. 14, 1922.

Application filed February 18, 1921. Serial No. 445,992.

To all whom it may concern:

Be it known that I, ADELARD E. RAVENELLE, a citizen of the United States, residing at Norwich, in the county of New London and State of Connecticut, have invented certain new and useful Improvements in a Lay-Mark Preventer; and I do hereby declare the following to be a full, clear, and exact description of the invention, such as 10 will enable others skilled in the art to which it appertains to make and use the same.

The object of the invention is to provide means for preventing lay marks in woven fabrics, or to provide an indicator whereby 15 the weave line of fabrics in a loom and in the course of production may be accurately adjusted with relation to the path of movement of the lay to avoid the crowding of the picks when the loom is restarted after the 20 operation thereof has been interrupted and to prevent a loose or widely spaced arrangement of the picks, one fault resulting in what is known as a heavy lay mark and the other in a light lay mark, due to the fact 25 that when the machine is set to produce a fabric having a specified number of picks to the inch, should the operation be interrupted for any cause and it be necessary for the operator or weaver to pick out or 30 remove some of the fibres, thereby dislocating the weave line of the woven fabric with relation to the path of movement of the lay, his readjustment of the weave line must be absolutely accurate or the machine upon being 35 restarted will lay the fibres too close together for a certain distance or too far apart throughout a number of picks or operations, with the result of laying either an extra thickness or closeness of the fibres or picks, 40 or a looseness or undue separation thereof constituting what is known as above indicated as either a heavy or a light lay mark; and it is with the object of enabling the weaver after such an interruption of the 45 operation of the loom to readjust the weave line with absolute accuracy and without loss of time so as to enable him to resume the weaving operation where it was interrupted and lay the picks at exactly the right intervals in accordance with the setting of the machine and the portion of the fabric already woven, to the end that the possibility of forming lay marks may be avoided, that the mechanism forming the subject of invention 50 has been devised; and the same consists in a construction, combination, and arrange-

ment of parts constituting an apparatus which may when not in use be conveniently stored under or adjacent to the loom in position for imminiate use when required, a 60 preferred embodiment of such mechanism being illustrated in the accompanying drawing, wherein:

Figure 1 is a front view of the apparatus arranged in operative relation with a loom, 65 a portion of which is shown to indicate the mode of operation of the apparatus.

Figure 2 is a side view of the same.

Figure 3 is an enlarged detail view of the head of the apparatus. 70

Figure 4 is a view of the gage arm detached.

Figure 5 is a similar view of the crank shaft.

The apparatus consists essentially of a 75 head indicated generally at 10, which is adapted to normally occupy a position beneath the loom indicated generally at 11 or beneath the plane of movement of the woven fabric and the mechanism by which the 80 same is produced, under such conditions as to adapt it to be moved into the plane of the fabric when required to justify the weave line in the resetting of the woven portion of the fabric after an interruption of the operation of the loom, and to provide for such movement of the head it may be supported by a vertically movable plunger rod 12, mounted in suitable guides 13 and 14 upon a standard 15 having a suitable base 16 which 85 may be bolted or otherwise secured to the floor, a treadle 17 being arranged in operative relation with the plunger rod and mounted upon a suitable bracket 18, a cushion spring 19 serving to relieve the jar on the head when 90 pressure is removed from the treadle to permit the mechanism to drop from the plane of the fabric. 95

The justifying mechanism in the illustrated embodiment of the invention consists 100 of a U-shaped bracket 20 of which the lower arm 21 is adapted to be bolted to the head 22 at the upper end of the plunger and a gage arm 23 fulcrumed upon the upper arm of the bracket and carrying offset blades 24 105 of which the extremities are adapted to be projected upward between the threads of the warp indicated at 25 and with their edges in contact with the fabric at the weave line, the woven portion of the fabric being indicated at 26. This gage arm is of pendulous construction, having the counter-weight 27 110

which yieldingly holds the blades 24 in the proper position while permitting the deflection thereof if the weave line of the fabric is too far advanced and which thereby indicates that the weave line is out of position and should be moved in order that the further resumed operation of the loom may not cause a heavy lay mark by crowding the weft threads in the beating movement of the 10 lay.

Connected with the gage arm is an indicator mechanism consisting of a pointer 28 traversing a dial plate 29 supported by the bracket 20 and having a suitable normal or 15 unit mark 30 to which the pointer should be directed when the gage arm is in its normal position with the edges of the blades 24 in light touching contact with the weave line of the fabric.

20 In the construction illustrated, motion is communicated from the gage arm to the pointer by means of a crank shaft 31 having a terminal spindle 32 mounted in a bearing in the bracket 20 and carrying the pointer, 25 and having at its opposite end a pin 33 arranged in a slot 34 of the gage arm near the lower or weighted end thereof so that a very slight deviation of the gage arm from its normal or truly vertical position will be 30 multiplied in the representation thereof by the pointer upon the dial plate and will indicate unmistakably to the operator that adjustment of the weave line is necessary. Obviously if the weave line is too far back and 35 is out of contact with the edges of the blades 24 the fact may readily be determined by a slight swinging movement of the gage arm. When the edges of the blades are in light contact with the weave line and the 40 pointer is directed to the unit or neutral mark 30 of the dial, the weaver is advised that the fabric is in proper position to resume the operation of the loom without possibility of producing a lay mark.

45 Owing to the fact that the apparatus may be thrown into operative relation with the fabric merely by pressure upon the treadle, it will be obvious that the adjustment of the weave line of a fabric after an interruption of 50 the operation of a loom, may be effected promptly as the device will instantly indicate whether or not the weave line is in the proper position and the direction in which it must be moved in order that it may 55 occupy the proper position, and as a consequence much loss of time may be avoided in the setting of the fabric and the reduction of the value of the fabric by producing lay marks therein which involves a well recognized commercial depreciation, may be 60 avoided, it being a well known fact that only the most skillful weavers can properly adjust the weave line merely by testing the same through the movement of the lay or otherwise, and then only by the exercise of 65

the utmost care and under conditions involving a considerable expenditure of time.

The lay preferably carries a bumper protector 34 for preventing movement thereof when the apparatus embodying the invention is in operative position, and in order to prevent the movement of the apparatus into operative position while the loom is running or until the movement thereof has been stopped, there is preferably employed a 75 gravity latch 35 adapted to normally occupy the position in the path of the treadle 17 and connected by a link 36 with the starting lever 37 of the loom so that when the latter is drawn to the stopping position indicated in 80 Fig. 2 the latch is withdrawn from the path of the treadle to permit of the elevation of the gaging apparatus whereas when the hand lever is moved toward the machine to start the loom the latch is permitted to drop 85 into the path of the treadle and lock it against movement.

Having thus described the invention, what I claim is:

1. An apparatus for the purpose described 90 having a weave line indicator movable in a path perpendicular to the plane of movement of the fabric and supported by a treadle actuated plunger.

2. An apparatus for the purpose described 95 having a weave line indicator movable toward and from the plane of movement of the fabric and provided with a pendulous gage arm.

3. An apparatus for the purpose described 100 having a weave line indicator movable toward and from the plane of movement of the fabric and provided with a pendulous gage arm, and a cooperating index for registering deflections of the indicator from 105 the normal position.

4. An apparatus for the purpose described 110 having a weave line indicator movable toward and from the plane of movement of the fabric and provided with a pivotal counter-weighted gage arm having blades for interposition between the warp threads and edge contact with the weave line.

5. An apparatus for the purpose described 115 having a weave line indicator movable toward and from the plane of movement of the fabric and provided with a pivotal counter-weighted gage arm having blades for interposition between the warp threads and edge contact with the weave line, and a 120 pointer operatively connected with the gage arm and traversing a dial plate.

6. An apparatus for the purpose described 125 having a weave line indicator movable toward and from the plane of movement of the fabric and provided with a pivotal counter-weighted gage arm having blades for interposition between the warp threads and edge contact with the weave line, and a pointer operatively connected with the gage 130

- arm and traversing a dial plate, said connection consisting of a crank shaft carrying the pointer and having slotted connection with the gage arm.
- 5 7. An apparatus for the purpose described having a weave line indicator movable toward and from the plane of movement of the fabric and provided with a weave line contacting element yieldingly movable in 10 the direction of movement of the fabric, said indicator being carried by a movable frame, a treadle for actuating said frame, and a latch, actuatable by the starting lever of the loom for locking the treadle against movement.
- 15 In testimony whereof I affix my signature in presence of two witnesses.
